[57] CLAIM

The ornamental design for a fruit/vegetable netting display hammock, as shown and described.

DESCRIPTION

FIG. 1 is a perspective view of the display hammock showing my new design taken from the front and to one side;

FIG. 2 is an end elevational view thereof;

FIG. 3 is a top plan view thereof;

FIG. 4 is a side elevational view thereof; and,

FIG. 5 is a bottom view thereof.

The broken lines showing outlines of fruit in FIG. 1 are for illustrative purposes only and form no part of the claimed design.
